UNITED STATES PATENT OFFICE.

GIOVANNI GAGLIO AND LUIGI VILLANI, OF MILAN, ITALY.

SWITCH.

No. 918,434.

Specification of Letters Patent.

Patented April 13, 1909.

Application filed November 2, 1907. Serial No. 400,420.

To all whom it may concern:

Be it known that we, GIOVANNI GAGLIO, post-office official, and LUIGI VILLANI, electrician, subjects of the King of Italy, residing at Milan, Italy, have invented new and useful Improvements in Switches, of which the following is a specification.

This invention relates to a time switch device of that type wherein a sand glass or like device is used and by means of which special devices are brought into circuit closing position and so remain until the sand or other material in the glass has passed from one portion thereof into another part of the same.

The primary object of the invention is to provide a simple and effective switch of the character specified having a positive operation and reliable in the performance of its function, the switch being wholly automatic in its operation and preventing any waste of current, as it does not contain any devices which would have the tendency to utilize current in a wasteful manner.

The present switch has been devised particularly for use in connection with electric lamps and to control the latter as to their lighted and extinguished condition through the medium of a movable device, such as a door.

The switch may also be used for signaling purposes interrupting the flow of liquids or gases by controlling the actuation of valves or for any other purpose embodying an electric circuit or circuits which may be opened or closed by the switch.

In the accompanying drawing, a preferred embodiment of the invention is illustrated to demonstrate one practical form of the apparatus, and therein: Figure 1 is a longitudinal section through the switch or showing one of the frame plates or members removed and particularly illustrating the switch in a position of rest. Fig. 2 is a diagrammatic view showing the switch organization in circuit closing position. Fig. 3 is a section taken transversely through the switch organization in the plane of the line $x-y$, Fig. 1.

The apparatus comprises two plates a and b which are suitably spaced and form a frame, a wheel i being carried by and projecting below the frame for engagement with a rod l projecting from a door or other movable device, as shown in connection with Fig. 1, the rod l being brought into contact with the wheel i when the door is opened. The

wheel i is mounted on a pivoted arm j attached to the plate a and the wheel is therefore free to oscillate within certain limits. The periphery of the wheel i is preferably grooved and provided with a resilient or rubber ring k cylindrical in cross-section to operate as a buffer or to produce a cushioned contact in a manner which will be presently explained. The wheel i supported as specified may be properly termed an actuator, and to render the arm l effective it is preferably formed of resilient material and of such dimensions as to be positive in its operation with relation to the said wheel i .

The switch mechanism proper consists of an hour-glass containing liquid or powder, the passage of the latter from one bulb to the other requiring a determined lapse of time. The hour-glass c is inclosed within a metallic tube or casing d to prevent breaking the same, the said casing for the hour-glass being rotatable through the medium of suitable pins e mounted in the plates a and b . At one side of the casing d a cam f of suitable material and with concaved edges is mounted on one of the pins e to move the said tube or casing simultaneously therewith, and on this cam is fixed an electrical switch g against which, at diametrically opposite points, two copper springs h have bearing and act as brushes. The supporting means for the springs h are adapted to have the circuit wires attached thereto in any suitable manner, and the switch g is so constructed that it will make the circuit when the springs or brushes h are in one position thereon and break the circuit when the said springs or brushes occupy another position on the said switch. The switch g is rotated with the tube or casing d or with the cam f and said tube or casing, and the tube or casing carrying the hour-glass is thrown over from one position to another by the wheel i which is brought into contact therewith, as will be more fully hereinafter explained.

Projecting outwardly from the tube or casing d are studs m and q , the said studs being at opposite extremities of the casing and adapted to respectively engage a locking pawl n and a lever o having a depending contacting arm o^1 adjacent to its fulcrum point and a counterpoise weight p and in an opposite operation or when the tube or casing d and the hour-glass c are overturned by the wheel i through the medium of the cam f , the stud m will ride downwardly over the pawl n .

and engage the end of said pawl to hold the tube or casing and hour-glass in fixed adjusted position and the stud *q* will rest adjacent to the arm *o*¹ of the lever *o*, and when 5 the parts are restored to the position shown by Fig. 1 the said stud *q* will contact with the arm *o*¹, raise and pass the lever, and move over the pawl *n*, and the stud *m* will continue upwardly and likewise pass the arm *o*¹ of the 10 lever *o*. It will be seen, therefore, that the pawl *n* serves as a locking means and the lever *o* with its counterpoise weight controls the movement of the tube or casing *d* and hour-glass *c* to prevent too rapid overturning 15 and overcome any tendency to breakage and displacement of the spring arms or brushes *h* or fracture of the hour-glass. It will be understood that the hour-glass, by reason of the change of position of the liquid or sand 20 therein, will be sufficient to operate a tube or casing at intervals.

Let it be presumed that the apparatus is fixed above a door to which the yielding rod or analogous device *l* is secured, and that the 25 apparatus is in the position of rest as shown by Fig. 1. When the door is opened the rod or analogous device *l* will contact with and press against the wheel *i* and gradually raise the said wheel until it engages the adjacent 30 portion of the cam *f* and the continued opening movement of the door and the tendency of the rod or analogous device *l* to pass under the wheel will cause the said wheel to rotate in the direction of the arrow, shown by Fig. 1, 35 and impart a turning movement to the cam *f* in the direction of the arrow thereon and throw the tube or casing *d* containing the hour-glass over in the direction of the arrow at the upper right-hand portion of Fig. 1. 40 This movement of the tube or casing will cause the stud *m* to pass downwardly over the pawl *n* and any backward movement of the tube or casing will be obstructed by the said stud *m* engaging the lower free end of 45 the pawl and the parts will then be in the position shown by Fig. 2. The cam *f* as shown has opposite convex extremities and intermediate concave sides and the wheel *i* frictionally engages with one of the convex extremities and enters the following concave side and holds the tube or casing against 50 movement that might ensue from momentum if there was no restriction to such movement.

55 In the position of the parts shown by Fig. 2 the circuit is closed, and when the door is again closed, the rod or analogous device *l* and the wheel *i* assume the position shown in Fig. 2 by reason of the fact that the said 60 rod *l* is released from the wheel *i*. The sand or liquid, which has been located in the lower portion of the hour-glass prior to the overturning movement as just explained, will by such overturning movement be disposed at the upper portion of the apparatus 65

and the empty bulb will then be at the lower portion of the apparatus and the tube or casing carrying the hour-glass by reason of the preponderance of weight at its upper portion, will have a tendency to return to 70 normal position, but this tendency will be obstructed by the stud *m* engaging the pawl *n*, as hereinbefore explained, and consequently the two springs or brushes *h* positively close the circuit through the switch 75 *g*. As the sand or liquid passes from the upper bulb to the lower bulb of the hour-glass the weight increased at the bottom or lower extremity of the tube or casing will cause the said tube or casing and parts co-operating therewith to again assume the position shown by Fig. 1, turning in the direction of the arrow or from right to left. A complete overturning movement of the tube or casing will, however, be prevented from 80 the position shown by Fig. 2 by the stud *g* engaging the arm *o*¹ of the lever *o*, and it will be understood that the casing does not assume an upright position until a given quantity of sand has fallen into the lower 90 bulb and which will be so timed as to permit the circuit to remain closed long enough to accomplish a desired purpose or function. It will be understood that when the casing assumes its vertical position the circuit is 95 broken, and if the circuit includes lamps, the latter will be simultaneously extinguished.

The apparatus may be varied in dimensions to adapt it for different applications, and it may be generally employed wherever 100 it is desired to open and close an electric circuit for a certain length of time.

What is claimed is:

1. An electric time switch operating mechanism comprising a device having an overturning movement and containing a counterpoise medium which varies its position therein, a switch carried by the said device, circuit brushes engaging the switch, a rotatable friction means movable in relation to 105 and engageable with a part of said device, and movable means for operating said rotatable friction means.

2. An electric time switch operating mechanism comprising a device having an overturning movement and containing a counterpoise medium which varies its position therein, a switch carried by said device, circuit terminal means engaging the switch, a cam carried by the said device, a rotatable 115 friction means movable in relation to the said cam and adapted to have contact with the latter, and movable means for operating said rotatable friction means.

3. An electric time switch operating mechanism comprising a switch having an overturning device connected thereto and provided with variable counterpoise means therein, circuit terminal means engaging the switch, and rotatable frictional means mov- 125 130

able into engagement with a portion of the overturning device for actuating the latter.

4. An electric time switch operating mechanism comprising a switch having means for changing the position thereof provided with variable weight shifting instrumentality, circuit terminal means engaging the switch, and rotatable friction means movable into engagement with a portion of the said means for changing the position of the switch for actuating the position changing means.

5. An electric time switch operating mechanism comprising a switch having a rotatable device connected thereto and provided with variable counterpoise means therein, circuit terminal means engaging the switch, means for preventing the return of the

switch and rotatable device to inoperative position until the variable counterpoise means has moved from one position to another in the said rotatable device, and rotatable frictional means movable into engagement with a portion of the rotatable device to dispose the latter and the switch in operative position.

In testimony whereof we have signed our names to this specification in the presence of two subscribing witnesses.
